UNITED STATES PATENT OFFICE.

ANDREW PILLATT, OF NOTTINGHAM, ENGLAND, ASSIGNOR OF ONE-HALF TO
JOHN THORPE PERRY, OF SAME PLACE.

CYCLE-SADDLE.

SPECIFICATION forming part of Letters Patent No. 600,799, dated March 15, 1898.

Application filed September 19, 1896. Serial No. 606,442. (No model.)

To all whom it may concern:

Be it known that I, ANDREW PILLATT, a subject of the Queen of Great Britain and Ireland, residing at Nottingham, England, have 5 invented a new and useful Cycle-Saddle, of which the following is a specification.

This invention relates to improvements in cycle-saddles, and is designed to provide a peakless saddle suitable for either ladies' or 10 gentlemen's use which shall be free from the anatomical objections which apply to the ordinary or peaked form of saddle.

According to my invention I form the saddle as a hollow cushion of rubber having a flat 15 base and an upper part or crown which is arched or of convex form and is sufficiently thick to give a resilient support to the rider without being pressed down upon its base or under part.

20 This saddle is of approximately circular form, but has at its front part, where the peak is usually situated, a curved or segmental recess or indentation in order to avoid perineal pressure. On each side of this recess or indentation the saddle is so shaped as to give 25 to its front a wave-like appearance.

A vent or air-inlet is provided—say in the base of the saddle—to allow the air to freely enter and leave it and to permit of its resum- 30 ing its normal shape on the rider dismounting.

The saddle rests in or upon a suitable support or frame secured to the saddle-stalk, and its base is provided with studs or projections which enter corresponding holes or recesses 35 in the said support or frame and so prevent accidental shifting or displacement.

In the accompanying drawings, Figure 1 is a plan of a saddle constructed according to my invention. Figs. 2 and 3 are sections on 40 the lines $x-x$ and $y-y$ of Fig. 1, respectively. Fig. 4 is an under side view of the saddle. Fig. 5 is a plan of the support on which the saddle rests, and Fig. 6 is a section of the said support on the line $z-z$ of Fig. 5.

45 The saddle consists of the upper or seat portion a , forming an arched or convex crown, and the base or under portion a' , and between which portions is comprised the air space or cavity a^2 . The crown or seat part of this sad-

dle gradually increases in thickness from the 50 base upward and is sufficiently strong to support the weight of the rider without collapsing and touching the base.

b is the segmental recess or indentation in the front of the saddle, and c are the rounded 55 portions on each side of this recess, which complete the wave-like or curvilinear form of the front of the saddle.

d is the vent or air-inlet, by which free in- 60 gress and egress of the air are permitted. This vent may advantageously have its edge pro- tected or strengthened by a metallic eyelet d' .

e is the support or frame on which the saddle rests. It is constructed lightly of metal 65 or other suitable material and in any con- venient manner—as, for example, by stamp- ing out of sheet metal or by interlacing metal strips after the manner of lattice-work.

f is the saddle-stalk, to which the support 70 e is secured in any convenient manner.

g are the studs or projections on the base of the saddle, which may be conveniently cast or molded in one therewith. h are the holes or recesses in the support e , into which the 75 said studs engage or fit for the purpose of preventing shifting of the saddle. For this purpose likewise the support may be formed with a raised edge or bead e' .

It will thus be apparent from this construc- 80 tion that as the upper part a of the saddle is of sufficient thickness and strength to resist being pressed into contact with the base a' and closing the vent, and as there is no valve nor any compressed air inside the saddle, the action is essentially different from that of the 85 pneumatic class of saddle in that the rider is supported by the natural resiliency of the material of the saddle in conjunction with the free air which is always present inside my saddle. In addition to this the air in the 90 space or cavity a^2 helps to minimize sudden shocks to the cycle, seeing that as such air cannot momentarily pass bodily through the air-vent it temporarily forms an air-cushion.

Having now described my invention, I 95 claim—

A cycle-saddle having a wave-like front constituting a segmental recess, a base, a rear

portion circular in plan view and arched to form a resilient seat of sufficient strength in itself to support the rider above the base, and an air-space existing throughout the saddle 5 and provided with an open but restricted air-vent, substantially as described.

In witness whereof I have hereunto signed

my name in the presence of two subscribing witnesses.

ANDREW PILLATT.
